(57) **CLAIM**

The ornamental design for an instrument for suspending reinforcements for a telegraph pole, as shown and described.

DESCRIPTION

FIG. 1 is a front perspective view of an instrument for suspending reinforcements for a telegraph pole;

FIG. 2 is an enlarged front perspective view thereof;
FIG. 3 is a front view thereof;
FIG. 4 is an enlarged front view thereof;
FIG. 5 is a rear view thereof;
FIG. 6 is an enlarged rear view thereof;
FIG. 7 is a top plan view thereof;
FIG. 8 is an enlarged top plan view thereof;
FIG. 9 is a bottom view thereof;
FIG. 10 is an enlarged bottom view thereof;
FIG. 11 is a right side view thereof;
FIG. 12 is an enlarged right side view thereof;
FIG. 13 is a left side view thereof;
FIG. 14 is an enlarged left side view thereof;
FIG. 15 is a reference view indicating how the article is used;
FIG. 16 is a front perspective view of the instrument for suspending reinforcements for a telegraph pole;
FIG. 17 is an enlarged front perspective view thereof;
FIG. 18 is a front view thereof;
FIG. 19 is an enlarged front view thereof;
FIG. 20 is a rear view thereof;
FIG. 21 is an enlarged rear view thereof;
FIG. 22 is a top plan view thereof;
FIG. 23 is an enlarged top plan view thereof;
FIG. 24 is a bottom view thereof;
FIG. 25 is an enlarged bottom view thereof;
FIG. 26 is a right side view thereof;
FIG. 27 is an enlarged right side view thereof;
FIG. 28 is a left side view thereof;
FIG. 29 is an enlarged left side view thereof; and,
FIG. 30 is a reference view indicating how the article is used.
The broken lines are shown in the views for illustrative purposes only and form no part of the claimed design.
